UNITED STATES PATENT OFFICE.

MARTIN CASHIN, OF EAST PEPPERELL, MASSACHUSETTS.

MACHINE FOR COATING PAPER.

SPECIFICATION forming part of Letters Patent No. 758,169, dated April 26, 1904.

Application filed May 16, 1903. Serial No. 157,440. (No model.)

To all whom it may concern:

Be it known that I, MARTIN CASHIN, a citizen of the United States, residing at East Pepperell, in the county of Middlesex and State of 5 Massachusetts, have invented a new and useful Machine for Coating Paper, of which the following is a specification.

This invention is an improved construction of paper-coating machine, the object being to 10 provide a machine which will apply color to both sides of the paper at the same operation and one which will effectively and evenly apply the color and work the same in thoroughly, thereby avoiding any streaky appearance of 15 the paper after being coated.

Another object of the invention is to provide a machine by means of which different colors can be applied to the opposite faces of the paper, if so desired.

With these objects in view the invention consists, essentially, in providing a frame comprising a vertical and a horizontal portion, the vertical portion carrying drums over which paper passes and brushes for applying 25 the color thereto, said brushes rotating in a direction opposite the movement of the paper, the horizontal portion of the frame carrying a series of transversely-reciprocating brushes adapted to operate simultaneously upon opposite sides of the paper in directions transverse 30 to the movement of the paper.

The invention consists also in certain details of construction and novelties of combination, all of which will be fully described 35 hereinafter, and pointed out in the claims.

In the drawings forming part of this specification, Figure 1 is a side elevation of a machine constructed in accordance with my invention. Fig. 2 is a vertical longitudinal 40 sectional view of the same. Fig. 3 is an end view, partly in section. Fig. 4 is a top plan view of the vertical portion of the machine, the top brushes being removed in order to more clearly illustrate the other features of 45 the invention. Fig. 5 is a transverse sectional view on the line 5-5 of Fig. 1. Fig. 6 is a side elevation showing the main portions of a slightly-modified form of machine, the modification residing mainly in the gearing

devices for operating the brushes and drums; 50 and Fig. 7 is a detail view.

In carrying out my invention I employ a main frame A, comprising a vertical portion A' and a horizontal portion A². This main frame A may be constructed of wood or 55 metal, as preferred, and the general arrangement of the beams and cross-pieces is to a very large extent immaterial. A paper-roll B is journaled upon the vertical portion A', the strip of paper passing under an idler C, carried by the frame, and over a drum D, journaled at the upper end of the vertical portion 60 of the frame. The paper then passes under another drum D' and then passes out centrally through the horizontal portion of the 65 main frame to the drying rack or frame. (Not shown.) As the paper passes over the drum D color is applied to one face thereof by means of a rotary brush E, and as the paper passes under the drum D' color is applied to the opposite face by means of a rotary brush E', said rotary brushes E and E' receiving the 70 color from feed-rollers E² and E³, respectively, which are journaled in the fountains E⁴ and E⁵, respectively. In this manner color 75 is applied to both faces of the paper as it passes through the machine, and it is obvious that different colors can be applied to the opposing faces. An adjustable reciprocating brush F is arranged at the top of the vertical 80 portion of the frame and is adapted to spread the color evenly upon the paper while passing over the drum D, and an adjustable reciprocating brush F' is arranged beneath the drum D' and serves to evenly spread the color 85 upon the opposite face of the paper while passing under the drum D', and for the purpose of thoroughly spreading and working in the color upon both sides I employ a series of 90 transversely-reciprocating brushes G, which are arranged in the horizontal portion of the main frame above and below the paper, said brushes being adjustable, as hereinafter described. It will thus be seen that I provide for applying the color to both faces of the 95 paper and work the said color thoroughly, thereby avoiding any streaky appearance to the coated paper.

I shall now describe the means for rotating the drums and rotary brushes, together with the means for operating the reciprocating brushes, said means being those which I consider best adapted for the purpose intended; but it will be understood that these means may be varied or changed without departing from the broad principle of my invention.

A main drive-shaft H is journaled horizontally in the vertical portions of the main frame and receives its power in any suitable manner. A gear-wheel H' is mounted adjacent the end of the shaft H and is adapted to mesh with a gear I', mounted upon the end of the shaft I, and the gear I' also meshes with a gear K, mounted upon the end of the shaft carrying the drum D, and by means of which said drum is rotated, said gear meshing with a gear L, mounted on the side of the frame, which in turn meshes with a gear M, mounted upon one end of the shaft carrying the brush E. The gear H' also meshes with a gear K', mounted upon the end of the shaft carrying the drum D', and by means of which the said drum is rotated, and this gear K' also meshes with the gear L', which in turn meshes with a gear M', mounted upon the end of the shaft carrying the brush E', and by means of which said brush is rotated, the gears L and L' being employed to rotate the brushes in a direction opposite the movement of the paper. The shaft H also carries a beveled gear N, which meshes with a beveled gear N', mounted upon the upper end of a shaft O, journaled in brackets O' and carrying a beveled gear P, which meshes with a beveled gear P', mounted upon the end of a shaft Q, journaled in brackets Q', said shaft Q operating a parallel horizontal shaft Q² by means of a belt Q³ and pulleys Q⁴. The shafts Q and Q² have the eccentrics R and R' mounted thereon, to which straps S and S', respectively, are connected, said straps having pitmen S² and S³ connected thereto, which pitmen are in turn pivotally connected to the reciprocating brushes G, and the eccentrics R and R' are arranged in vertical alinement upon the shafts Q and Q², and they are also arranged in such a manner that while the brushes connected with the eccentrics move in unison above and below the paper each alternate pair of brushes move in opposite directions. Each brush G comprises the fibers G¹, the head G², and a box G³, in which the head G² is adjustable by means of the adjusting-screws G⁴. Each box G³ has guiding-ribs G⁵ upon the opposite sides, which travel in the grooved guides G⁶, extending transversely across the horizontal portion of the main frame both above and below the paper. The feeding of the color to the paper is regulated through the medium of the upper cone-pulleys T and the lower cone-pulleys U, together with the belts T' and U', respectively, the upper pulleys being driven by means of a belt T², which

extends around a pulley carried by the drum-shaft and over a pulley mounted upon the end of one of the cone-pulley shafts, the opposite cone-pulley shaft having a pulley T³, over which travels a cross-belt T⁴, driving the pulley T⁵, mounted upon the end of the shaft carrying the feed-roller E². The lower cone-pulleys receive their power from the lower drum-shaft and transmit it to the lower feed-rolls E³, belts U² and U³, together with the necessary pulleys, being employed for this purpose. The feed-rolls E² and E³ are adjustable vertically by means of screws V, and the rotary brush E is adjustable horizontally by means of the screws V'. In the construction shown in Fig. 6 I employ two additional gears W and W', which are interposed between the gears K and L and K' and L'.

By means of a machine constructed as herein shown and described I am enabled to effectively carry out all of the objects hereinbefore referred to, and the operation of the machine is as follows: The paper carried upon the paper-roll is passed under the idler C, over and around the drum D, under the drum D', and out between the reciprocating brushes, where it is carried in any suitable manner to a drying rack or frame, and power being transmitted to the shaft H the drums D' and D will be rotated, and the gearing connected with the main drive-shaft will cause the brushes E and E' to first take the color from the feeding-brushes E² and E³, rotating in their respective fountains, and these rotary brushes E and E' will then apply the color to the opposite faces of the paper strip, said brushes rotating in a direction opposite to the movement of the paper. The stationary brushes F and F' serve to spread the color upon the paper as the said paper passes over the drum D and under the drum D'. These brushes F and F' are adjustable by means of the regulating-screws, so that any desired pressure can be had upon the said brushes. After the coloring-matter has been applied to both faces of the paper in the manner described the paper is carried out in a horizontal direction between the series of horizontally-reciprocating brushes G, there being six brushes, three above the paper and three below the paper, said brushes being arranged in pairs, as shown, and these brushes are operated by means of eccentrics arranged upon the shafts Q and Q², the shaft Q receiving its motion from a vertical shaft O, which carries a beveled gear at its upper end which meshes with a beveled gear carried by the main shaft H, and also another beveled gear which transmits motion to the shaft Q by meshing with the beveled gear carried by the said shaft Q, and inasmuch as the shafts Q and Q² are connected by means of a belt Q³ the said shafts will move in unison, and each pair of brushes will be caused to slide horizontally across the main frame, thereby thoroughly working in the color upon both faces

of the paper, and as each alternate pair of brushes operates in opposite direction the paper will not be pulled to one side or the other in its passage through the machine. The 5 amount of color is regulated by means of the upper and lower set of cone-pulleys, which receive their power from the upper and lower drums and transmit it to the upper and lower feed-rolls, so that by increasing or decreasing 10 the speed of the feed-rolls the amount of color supplied to the rotary brushes can be correspondingly increased or decreased.

It may be said that the transversely-reciprocating brushes F and F' are operated by eccentrics F², carried by the shaft O, and their construction and arrangement are exactly like those of the brushes G.

Having thus fully described my invention, what I claim as new, and desire to secure by 20 Letters Patent, is—

1. In a machine for coating paper the combination with the main frame comprising the vertical and horizontal portions, the rotary drums arranged in the vertical portion, rotary brushes arranged adjacent the rotary drums, means for feeding the said rotary brushes, and the horizontally-reciprocating brushes arranged in the horizontal portion of the main frame, together with means for rotating 25 the drums and rotary brushes, and means for reciprocating the horizontal brushes, as set forth.

2. In a machine of the kind described, the combination with the main frame, of the drums arranged therein, the rotary brushes, feed-rollers and fountains, transversely-reciprocating brushes arranged in pairs above and below the line of travel of the paper, means for rotating the drums, rotary brushes and feed-rolls together with means for reciprocating 35 the transversely-movable brushes, substantially as described.

3. In a device of the kind described, the combination with the rotary drum and means 40 for operating the same, a pair of cone-pulleys

and belt connecting the same, means for operating the said pulleys from the rotary drum, a rotary brush, a fountain, and feed-roll rotating in the fountain, together with means for connecting the cone-pulleys with the feed- 50 roll, as set forth.

4. In a device of the kind described, the combination with the upper and lower rotary drums, means for rotating the same, the rotary brushes adapted to apply color to the opposite faces of a sheet of paper passing around the drums, and the adjustable reciprocating brushes arranged above the upper drum and below the lower drum, substantially as specified. 55

5. In a device of the kind described, a horizontal brush, a box in which the head of said brush is adjustably held, said box having ribs upon the opposite side thereof, the grooved guides in which the ribbed box slides, together 60 with means for reciprocating said box, substantially as described.

6. The combination with the main frame comprising the vertical and horizontal portion, of the paper-roll support, the upper and lower drums, the upper and lower fountains, the upper and lower feed-rolls, the upper and lower rotary brushes, upper and lower adjustable reciprocating brushes, the transversely-movable horizontal brushes arranged in pairs above and below the line of travel of the paper, means for rotating the drums and rotary brushes, and means for reciprocating the transversely-movable brushes, the upper and lower cone-pulleys, means connecting the said 70 pulleys with the upper and lower drums, respectively, together with means for connecting the said pulleys with the upper and lower rolls, respectively, all of said parts being arranged and adapted to operate substantially 75 as described. 80
